United States Patent

Des. 239,371

Patented Mar. 30, 1976

239,371

CARTON BLANK

Glen R. Harrelson, Monroe, La., assignor to
Olinkraft, Inc., West Monroe, La.

Filed Sept. 26, 1974, Ser. No. 509,533

Term of patent 14 years

Int. Cl. D9—99

U.S. Cl. D9—245

FIG. 1

FIG. 2

FIG. 1 is a top plan view of a carton blank embodying my new design, the bottom being substantially the same in appearance.

FIG. 2 is a side elevational view of the carton blank shown in FIG. 1.

I claim:

The ornamental design for a carton blank, substantially as shown and described.
